CLAIM

We claim the ornamental design for an axially oriented peripheral sidewalled beverage container lid, as shown and described.

DESCRIPTION

FIG. 1 is an isometric top view of an axially oriented peripheral sidewalled beverage container lid;

FIG. 2 is an isometric bottom view thereof;
FIG. 3 is a top view thereof;
FIG. 4 is a bottom view thereof;
FIG. 5 is a front view thereof;
FIG. 6 is a right side view thereof;
FIG. 7 is a rear view thereof;
FIG. 8 is a left side view thereof;
FIG. 9 is a sectioned elevation left side view thereof, the section being taken in a direction of section line 9--9 of FIG. 3;
FIG. 10 is an enlarged detail view of area 10 circumscribed within FIG. 1;
FIG. 11 is an enlarged detail view of area 11 circumscribed within FIG. 2;
FIG. 12 is an enlarged detail view of area 12 circumscribed within FIG. 3;
FIG. 13 is an enlarged detail view of area 13 circumscribed within FIG. 4;
FIG. 14 is an enlarged detail view of area 14 circumscribed within FIG. 9; and,
FIG. 15 is an enlarged detail view of area 15 circumscribed within FIG. 9.
The dash-dash broken lines and the unshaded areas in between the dash-dash broken lines depict portions of the axially oriented peripheral sidewalled beverage container lid that form no part of the claimed design. The dot-dash-dot broken lines in FIGS. 1-4 and FIGS. 9-15 surrounding the detail areas and views form no part of the claimed design.
